UNITED STATES PATENT OFFICE.

RICHARD ESAU WHITE, OF HOUSTON HEIGHTS, TEXAS.

STOVE.

1,297,621.

Specification of Letters Patent. Patented Mar. 18, 1919.

Application filed April 9, 1917. Serial No. 160,592.

To all whom it may concern:

Be it known that I, RICHARD ESAU WHITE, a citizen of the United States, residing at Houston Heights, in the county of Harris and State of Texas, have invented certain new and useful Improvements in Stoves, of which the following is a specification.

This invention relates to new and useful improvements in stoves and has for its object the provision of a stove of the character described whereby kerosene and other similar oils may be utilized as fuel.

Another feature of the invention resides in the provision of a novelly formed burner pan upon which the fuel oil is fed and where combustion takes place.

A further feature of the invention resides in a novel means for admitting and regulating the draft to the combustion chamber.

A still further feature of the invention resides in the provision of baffles in the flue chamber to retard the current of heated air passing through said chamber and to thereby cause a greater radiation of heat.

With the above and other objects in view, the invention has particular relation to certain novel features of construction, operation and arrangement of parts an example 30 of which is given in this specification and illustrated in the accompanying drawings wherein:—

Figure 1 is a front view of the stove.

Fig. 2 is a side view thereof.

Fig. 3 is a transverse sectional view taken on the line 3—3 of Fig. 1.

Fig. 4 is a transverse sectional view taken on the line 4—4 of Fig. 2.

Fig. 5 is a vertical sectional view of the 40 burner pan, and

Fig. 6 is a transverse sectional view of the combustion chamber, showing a plan view of the burner therein.

Referring now more particularly to the 45 drawings wherein like numerals of reference designate similar parts in each of the figures, the numerals 1 and 2 refer, respectively, to the upper and lower compartments of the stove, said compartments being 50 approximately circular in cross section and being united by the front and rear walls 3 and 4 which are arcuate in cross section and are spaced apart so as to form a flue chamber 5 therebetween, said chamber communicating with the top and bottom compartments through the orifices 6 and 7, pro-

vided in the bottom 8 and the top 9, of the respective compartments 1 and 2. This particular contour of stove has been designed so as to give the maximum amount of heat 60 radiating surface. Near the front part of the lower compartment 2 is a combustion chamber formed of the four walls 10, said walls extending from the top to the bottom of the compartment and being fixed to said 65 top and bottom. The rear wall 10 of the combustion chamber as well as the rear wall of the compartment 2 have large transverse openings through which the draft pan 11 may be inserted, said pan extending to the 70 front wall of the combustion chamber and fitting closely therein. The rear part of the draft pan is of greater depth than the front portion thereof, as shown in Fig. 2, said front portion being abruptly offset relative to the rear portion, forming an abrupt shoulder which fits against the rear wall 10 of the combustion chamber as shown in Fig. 2. Within the combustion chamber and resting upon the draft pan is the burner 12, 80 which will be specifically described hereafter. The top of the compartment 2 has a circular opening 13 which is alined above the burner 12 and a perforated covering 14 is provided to cover this opening and standing from the top of the compartment 2 and surrounding the opening 13 are the bosses 15, which serve to keep the covering 14 in position and also to support any utensil which may be desirable to place on the 90 stove. The numeral 16 refers to a cylindrical container which is fixed to the stove by means of suitable anchors as 17, 17, said container being spaced a distance from the stove and provided to receive the fuel. 95 Leading from the bottom of the container 16 is a feed pipe 18 which extends through the wall of the compartment 2 and through the rear wall 10 and discharges on to the top of the burner 12. The flow of fuel 100 through the feed pipe 18 is controlled by means of the valve 19 of the usual and well known construction.

The burner 12 is shown in detail in Fig. 5, the same being approximately conical in 105 shape and being formed of sheet metal. This burner is punched full of perforations so as to throw up flanges 20 around each perforation, so that the oil which drips on to the burner from the pipe 18 will trickle 110 down the sides thereof without passing through the burner perforations.

The side walls 10 of the combustion chamber are provided with perforations 21 above the burner so as to permit the escape of the heated air from the chamber. The draft 5 is admitted to the burner through the ventilator 22 and through the opening 23 in said draft pan underneath the burner as well as through the orifices in the covering 14. Combustion takes place on the burner 10 12 and the heated air passes, as hereinbefore explained, through the orifices 21 and 7 and up through the flue chamber out through the orifice 6 into the compartment 1 and passes out thence through the pipe 22.

15 The flue chamber 5 is provided on opposite sides with spiraled baffles 24, 24, arranged in staggered relation. These baffles are provided to retard the current of heated air passing up through the chamber 5 and 20 thereby cause a greater radiation of heat.

What I claim is:

A stove including an upper and a lower chamber spaced apart, and a flue arcuate in cross section connecting said chambers, 25 spiraled baffles in the flue arranged in staggered relation, an inclosure in the front part of the lower chamber composed of four walls extending from the top to the bot-

tom of said chamber, the rear wall and the rear portion of the chamber having 30 alined transverse openings therethrough, a removable draft-pan inserted through said openings and extending up to the front wall of the inclosure, said pan having an opening in the top thereof and a draft inlet in 35 the rear end thereof, a removable conical shaped burner mounted on the pan above the opening in the top thereof, said burner being perforated, and its upper side being provided with upwardly extending flanges 40 to retard the flow of oil thereover, the walls of said inclosure having outlet orifices on each side above said burner, a fuel receptacle, a feed pipe leading therefrom and extending into the lower chamber and the 45 inclosure therein and discharging on said burner, the top of the lower chamber having an opening to permit access to the burner and a removable covering for said openings.

In testimony whereof I have signed my 50 name to this specification in the presence of two subscribing witnesses.

RICHARD ESAU WHITE.
